Application August 14, 1942, Serial No. 454,869

11 Claims. (Cl. 260—683.2)

This invention relates to the production of normal butylenes and relates more particularly to an improved process for the production of 2-butylenes from hydrocarbon mixtures comprising 1-butylenes and/or isobutylene.

Normal butylenes are finding application as starting materials in the production of an ever increasing number of vitally important derivative products. Often the efficient production of many of these products is dependent upon the availability of a substantially pure 2-butylenes feed. 10 However, the more readily available sources of butylene such as the butylene-containing hydrocarbon fractions obtained, for example, by treatments such as distillation and thermal or catalytic conversions of naturally occurring petroleum, natural gas, natural gasoline, distillate petroleum refinery products, and various other carbonaceous materials, generally furnish the normal and branched chain butylenes in admixture with one another. 2-butylenes in either or both of its isomeric forms, cis-2-butylenes and trans-2-butylenes, can be separated economically from hydrocarbon fractions comprising 1-butylenes and/or isobutylene by such methods as fractionation. Due to the proximity of their boiling points and their behavior under distillation conditions 1-butylenes and isobutylene can, however, not readily be separated from one another in such wise on a practical scale. Attempts to utilize methods known heretofore to convert substantially all of the butylene content of a hydrocarbon fraction to substantially pure normal butylene, preferably 2-butylenes, have often been found unsatisfactory due either to their complexity, cost of operation, or inability to effect conversions to the desired normal butylene isomer in the absence of substantial butylene polymerization or degradation. As a result processes which can utilize only the 2-butylenes, as well as even those processes which can use both of the normal butylene isomers, as starting material are generally constrained to use only the 2-butylenes content of the more readily available butene-containing hydrocarbon fractions. A process enabling the more efficient production of substantially pure normal butylene, particularly substantially pure 2-butylenes, from hydrocarbon fractions comprising a mixture of normal butylenes and isobutylene, in the absence of substantial polymerization reactions is therefore greatly desired.

It is an object of the present invention to provide an improved process for the more efficient

production of 2-butylenes from hydrocarbon mixtures comprising 1-butylenes and iso-butylenes.

Another object of the invention is to provide an improved process for the more efficient conversion of 1-butylenes to 2-butylenes.

5 A further object of the invention is to provide an improved process for the more efficient conversion of isobutylene to normal butylenes, more particularly to 2-butylenes. Other objects and advantages of the invention will be apparent from the following description thereof.

In accordance with the invention, a hydrocarbon mixture from any suitable source comprising, for example, saturated and unsaturated hydrocarbons having four carbon atoms to the molecule is fractionated in a feed fractionating zone 15 to separate a vapor fraction comprising 1-butylenes, isobutylene and isobutane from a liquid fraction comprising 2-butylenes and any normal butane present. The vapor fraction is contacted in 20 a first conversion zone with a catalyst and under well defined conditions which, it has been found, enable the efficient conversion of 1-butylenes to 2-butylenes in the absence of any substantial hydrocarbon polymerization or decomposition. Resulting 2-butylenes is separated from the effluence 25 of the first conversion zone as a final product and the remaining hydrocarbons comprising isobutylene are contacted in a second conversion zone 30 with a catalyst and at well defined conditions which, it has been found, effect the efficient conversion of isobutylene to normal butylenes. 2-butylenes is separated from the effluence of the second conversion zone as a final product and the remaining hydrocarbons comprising 1-butylenes are passed to the first conversion zone. In 35 one embodiment of the invention the accumulation within the system of isobutane, if present in the charge, is avoided by continuously or intermittently subjecting at least a part of the hydrocarbon stream passing from the first to the second conversion zone, to a treatment effecting the separation of at least a substantial amount of the paraffin hydrocarbons therefrom.

45 In order that the invention will be more readily understood, it will be described in detail with reference to the attached drawing forming a part of this specification and illustrating, more or less diagrammatically, one form of apparatus suitable for executing the invention.

50 A butylene-containing hydrocarbon mixture such as, for example, a butane-butylenes fraction separated by fractionation from the products of a thermal or catalytic hydrocarbon conversion process, is drawn from an outside source and

forced by means of pump 10 through valved line 11 into a feed fractionating zone. The feed fractionating zone may comprise, for example, a fractionator 12. The use of solvent extraction or solvent distillation steps, not shown in the drawing, may supplement the initial feed separation. Within fractionator 12 a vapor fraction comprising 1-butylene, isobutylene and any isobutane present is separated from a liquid fraction comprising 2-butylene and any normal butane present. The liquid fraction is withdrawn from fractionator 12 through valved line 13 and may be subjected to a subsequent treatment, by means not shown in the drawing, which may comprise, for example, solvent extraction or solvent distillation to effect the separation of 2-butylene from any normal butane admixed therewith. The vapor fraction is passed from fractionator 12 through line 14 and a cooling means, for example, condenser 15, into an accumulator 16.

From accumulator 16 the hydrocarbons are forced by means of pump 18 through valved line 19 into a heating zone. A part of this stream is diverted through valved line 20 as reflux to fractionator 12. Cooling means not shown in the drawing may be provided to cool the reflux stream. An indirect heat exchanger 22 is provided in line 19 to permit preheating of the stream by means of indirect heat exchange, for example, with a side-stream obtained within the system. The heating zone may comprise a furnace structure 23 containing an externally heated coil 24. Within coil 24 the hydrocarbon stream is heated to a temperature sufficiently high to maintain the desired temperature within the subsequent first conversion zone. The heated hydrocarbon stream is passed from coil 24 through line 25 into a first conversion zone. The first conversion zone may comprise an enlarged reaction chamber 26, containing a bed of suitable catalyst material capable of catalyzing the conversion of 1-butylene to 2-butylene. Though some conversion to the desired isomer can be obtained with several catalysts comprising aluminum oxide under certain conditions, it is essential to the attainment of the degree of operating efficiency enabling production of 2-butylene on a practical scale that substantially equilibrium conversion of 1-butylene to 2-butylene is obtained in the absence of any substantial polymerization or degradation of normal butylenes or isobutylene. The catalyst must in addition be of relatively low cost, be able to maintain its activity over long periods of operation and be capable of being regenerated by simple methods which can be repeated often without substantial detrimental effect to the catalyst.

It has now been found that these results are attained by the use of activated bauxite under well-defined conditions of operation. The bauxite may be activated by several methods comprising one or several of such steps as heating at elevated temperatures, for example, in the range of from about 500° C. to about 800° C., and treatment with steam or acid. A preferred catalyst comprises the activated bauxite sold by The Porocel Corporation under the trade-name "Porocel." A temperature in the range of from about 275° C. to about 400° C. and preferably between about 300° C. and 375° C. is maintained within reaction chamber 26. The conversion is effected at atmospheric pressure, although slightly elevated pressures, for example, up to about 100 lbs. and higher may be used if desired. The rate of flow through reaction chamber 26 is

carefully controlled to maintain a velocity of flow therethrough which in terms of liquid hourly space velocity will be in excess of about 5 and up to as high as, for example, about 150, and preferably between about 10 and 25. By the term "liquid hourly space velocity" as used throughout the specification and claims is meant the total amount of charge entering the reactor, measured in the liquid state, per unit volume of catalyst, per hour. Reduction of temperature substantially below the above-defined limit necessitates considerably reducing the throughput rate to obtain the desired high conversion to 2-butylene. Further, lowering both the temperature and flow velocity below the prescribed conditions causes a loss of a substantial amount of valuable butylenes due to polymerization reactions if pressures substantially above atmospheric are employed. Higher temperatures in the presence of this catalyst, on the other hand, result in substantial degradation of butylenes to undesired products.

The efficiency with which 1-butylene can be converted to 2-butylene in accordance with the invention, is illustrated by the following examples:

Example I

1-butylene was passed over activated bauxite, at atmospheric pressure and at the temperature and liquid hourly space velocities indicated in the following table. The amount of 2-butylene produced is given as percentage by weight of the product obtained:

Temp.	L. H. S. V.	2-butylene
350° C.	9	74.3
365° C.	18	74.7
350° C.	18	77.3
350° C.	70	70.2
350° C.	36	73.2

The formation of material higher boiling than C₄ hydrocarbons was too slight to be apparent.

Example II

A butane-butene hydrocarbon fraction, the composition of which is given in weight percent in column A of the following table, was passed over activated bauxite at 350° C. at a liquid hourly space velocity of 36 and at a pressure of 6 atmospheres. The composition of the products obtained after a three-hour period of operation is shown in weight percent in column B of the following table:

	A	B
<C ₄	0.6	0.5
Isobutylene	38.3	35.7
2-butylene	1.4	16.5
1-butylene	22.7	8.3
Butanes	36.5	36.2
>C ₄	0.5	2.8

The efficiency with which substantially selective conversion of 1-butylene to 2-butylene can be effected in accordance with the invention, when treating a mixture of hydrocarbons containing both saturated and unsaturated hydrocarbons having four carbon atoms to the molecule is clearly shown by the above example.

Decreasing the flow rate below the above-prescribed range to a substantial degree, even though a permissible operating temperature is maintained, causes olefin polymerization to take

place as a prominent reaction with a concomitant reduction in the amount of the desired 2-butylene produced, as illustrated by the following example.

Example III

1-butylene was passed over activated bauxite at a temperature of 315° C. and atmospheric pressure with a liquid hourly space velocity of 9. A conversion of 1-butylene to 2-butylene of 41.2% was obtained while the formation of material heavier than C₄ hydrocarbon was too small to be readily determined. A second experiment was conducted at substantially identical conditions with the exception that the liquid hourly space velocity was reduced to 3. Under the latter conditions, the reaction product consisted of 14.5% by weight of material heavier than C₄ hydrocarbons.

Effluence from reaction chamber 26 comprising 2-butylene, isobutylene, some unconverted 1-butylene, and isobutane, is passed through line 27 and a suitable cooling means, for example, a heat exchanger 28, into a fractionating zone. The fractionating zone may comprise a fractionator 29. Within fractionator 29 a liquid fraction comprising 2-butylene is separated from a vapor fraction comprising isobutylene, 1-butylene and isobutane. The liquid fraction is removed from fractionator 29 through valved line 30 and eliminated from the system as a final product. The vapor fraction is removed from fractionator 29 and passed through line 31, and a cooling means, for example a condenser 32, into an accumulator 33. A part of the stream passing through line 31 may be recycled through line 35 by means of pump 36 into line 19.

If a charge consisting essentially only of 1-butylene is to be converted to 2-butylene, it may be introduced directly into line 19 from an outside source by means of valved line 37. Such charge may constitute at least a substantial part of the charge to the system.

The products within accumulator 33 are withdrawn therefrom through valved line 39 and a part thereof may, if desired, be eliminated from the system. A part of the stream flowing through line 39 is passed through valved line 40 as a reflux to fractionator 29. In the preferred embodiment of the invention the hydrocarbon stream comprising isobutylene, 1-butylene, and isobutane not diverted through line 40, is forced by means of pump 41 through valved lines 39 and 42 into a heating zone. Line 42 is provided with a preheating means which may comprise an indirect heat exchanger 43. The heating zone may comprise a suitable furnace structure 44 housing an externally-heated coil 45. Within coil 45 the hydrocarbon stream is heated to a temperature sufficiently high to maintain the desired temperature conditions within a subsequent second conversion zone. From coil 45 the hydrocarbon stream is passed through line 46 into a second conversion zone.

The second conversion zone may comprise an enlarged reaction chamber 47. Within reaction chamber 47 the hydrocarbon stream is contacted with a catalyst material capable of catalyzing the conversion of isobutylene to normal butylenes. Though various catalyst materials have been proposed heretofore for conversion of normal butylenes to branched chain butylenes, such as for example the permutites, the activity of these catalysts is often not sufficiently pronounced to enable their satisfactory use in a practical scale conver-

sion of isobutylene to normal butylenes. These catalysts have been found, furthermore, to possess an undesirable tendency to catalyze the saturation of the olefinic charge. An added disadvantage of these catalysts resides in their inability to undergo frequent regenerations without substantial detrimental effect to their usefulness. It has now been found that certain activated aluminas are decidedly more active and permit the attainment of considerably longer operating periods. Activated bauxite, though highly advantageous for the conversion of 1-butylene to 2-butylene, is, however, considerably less efficient in its ability to catalyze the conversion of isobutylene to normal butylenes than activated alumina. In the preferred method of carrying out the invention, an activated alumina, and preferably an acid-washed activated alumina, is utilized as the catalyst within reaction chamber 47. The use of higher temperatures and lower space velocities than those prescribed for the conversion of 1-butylene to 2-butylene are necessary for the efficient conversion of isobutylene to normal butylenes. It has been found that a temperature within the range of from about 400° C. to about 600° C., and preferably from about 450° C. to about 550° C., and a liquid hourly space velocity in the range of from about 1 to about 15, and preferably not substantially in excess of about 10, substantially equilibrium conversions of isobutylene to normal butylenes are obtained in the absence of substantial polymerization or degradation reactions. Atmospheric or superatmospheric pressure up to, for example, about 100 lbs., or higher, may be maintained within reaction chamber 47. The efficiency with which isobutylene is converted to normal butylene under these conditions is evidenced by the following example.

Example IV

A hydrocarbon mixture consisting of 47.2% isobutylene, 51.9% butanes and 0.9% normal butylenes was passed over acid-washed activated alumina at a temperature of 500° C., atmospheric pressure, and at a liquid hourly space velocity of 3. Of the isobutylene charged, 60% was converted to normal butylenes, and the efficiency of normal butylene production was 95%, based on the total amount of isobutylene converted. No formation of normally liquid products was evidenced during the operation.

Effluence from reaction chamber 47 is passed through valved line 48 equipped with suitable cooling means, such as, for example, an indirect heat exchanger 49, into a fractionating zone. The fractionating zone may comprise a fractionator 50. Within fractionator 50 a liquid fraction comprising 2-butylene is separated from a vapor fraction comprising 1-butylene, some unconverted isobutylene and isobutane. The liquid fraction is withdrawn from fractionator 50 through valved line 51 and eliminated from the system as a final product. The vapor fraction is withdrawn overhead from fractionator 50 and passed through line 52, and a suitable cooling means, for example, a condenser 53 into accumulator 60. A part of the hydrocarbon stream flowing through line 52 may be recycled by means of pump 56 through line 57 into line 42.

If it is desired to convert a hydrocarbon stream consisting essentially of isobutylene to normal butylenes, this may be charged to the system through valved line 59 leading into line 42. Such an isobutylene stream may comprise at least a substantial part of the charge to the system.

Products accumulated within accumulator 60 are withdrawn therefrom through valved line 61 and a part thereof may, if desired, be removed from the system as a final product. A part of the hydrocarbon stream flowing through line 61 is passed through valved line 62 as reflux to fractionator 58. In the preferred embodiment of the invention substantially all of the hydrocarbons withdrawn from accumulator 60, not diverted through line 62, are forced by means of pump 10 63 through valved lines 61 and 64 into line 19 to be admixed therein with the charge to the first conversion zone. The 1-butlenes produced within reaction chamber 47 are thereby returned to the first conversion zone to be converted therein 15 to 2-butylene.

If normal butane is present to any substantial degree in the effluence of reaction chamber 47, the hydrocarbon stream may be diverted from line 48 through valved line 65 into feed fractionator 12.

Isobutane when present in the charge to the system is eliminated therefrom with a minimum loss of butlenes by continuously or intermittently removing at least a part of the hydrocarbon stream from line 38 through valved line 67 into a solvent extraction zone, comprising, for example, an extraction column 68. Within column 68 the hydrocarbon stream is contacted countercurrently with a suitable solvent such as, for example, a mixture of acetone and water, or any other solvent capable of selectively absorbing olefins, introduced into the extraction column by means of valved line 69. Unabsorbed isobutane is eliminated overhead from column 68 through valved line 70. The solvent containing the absorbed olefins is withdrawn from column 68 and forced by means of pump 71 through line 71 into a distillation zone, for example, a still 72 wherein the absorbed olefins are distilled from the solvent. The separated olefins are removed overhead from column 72 through valved line 73 and forced in part, or in their entirety, by means of pump 74, through line 75, into line 38 at a point beyond the inlet to line 67. Solvent freed of olefins is returned from the bottom of column 72 to the upper part of column 68 by means of line 76. In one embodiment of the invention, the proportion of the hydrocarbon stream which is diverted through line 67 is controlled so as to effect the removal of isobutane from the system through line 70 at a rate substantially equal to that at which this saturated hydrocarbon is introduced into the system. It is to be understood, however, that the invention is not necessarily limited to this particular method of isobutane removal, and, if desired, the isobutane may be removed at other points within the system, for example, by solvent extracting the hydrocarbon stream flowing through line 14, by means not shown in the drawing.

While the invention has been described in a detailed manner and examples provided illustrating suitable modes of its execution, it is to be understood that modifications may be made within the scope of the invention. Thus, for example, though in the drawing single enlarged reaction chambers are shown as constituting the conversion zones, it is to be understood that a plurality of such chambers connected in series or in parallel, and/or tubular catalyst-containing reactors, as well as suitable additional means for maintaining desired operating temperatures therein, may be comprised in each of said conversion zones. Additional solvent extraction or extractive distil-

lation steps may, if desired, be provided to aid any or all of the steps effecting the separation of hydrocarbons within the system.

I claim as my invention:

1. The process for the conversion of 1-butylene to 2-butylene in the absence of any substantial olefin polymerization which comprises contacting 1-butylene with bauxite at a temperature of from about 300° C. to about 375° C. and at a liquid hourly space velocity of from about 10 to about 25, said bauxite having first been subjected to a temperature of from about 500° C. to about 800° C. thereby rendering said bauxite active for the conversion of 1-butylene to 2-butylene in said conversion temperature range.

2. The process for the conversion of 1-butylene to 2-butylene in the absence of any substantial olefin polymerization which comprises contacting 1-butylene with bauxite at a temperature of from about 275° C. to about 400° C. and at a liquid hourly space velocity of from about 5 to about 150, said bauxite having first been subjected to a temperature of from about 500° C. to about 800° C. thereby rendering said bauxite active for the conversion of 1-butylene to 2-butylene in said conversion temperature range.

3. The process for the production of 2-butylene in the absence of any substantial olefin polymerization which comprises contacting a 1-butylene-containing hydrocarbon mixture consisting essentially of saturated and unsaturated hydrocarbons, having four carbon atoms to the molecule, with a catalyst comprising bauxite at a temperature of from about 275° C. to about 400° C. and at a liquid hourly space velocity of from about 10 to about 25, thereby effecting the conversion of 1-butylene to 2-butylene as the predominant reaction, said bauxite having first been subjected to a temperature of from about 500° C. to about 800° C. thereby rendering said bauxite active for the conversion of 1-butylene to 2-butylene in said conversion temperature range.

4. The process for the production of 2-butylene in the absence of any substantial olefin polymerization which comprises contacting a 1-butylene-containing hydrocarbon mixture consisting essentially of saturated and unsaturated hydrocarbons, having four carbon atoms to the molecule, with a catalyst comprising bauxite at a temperature of from about 275° C. to about 400° C. and at a liquid hourly space velocity of from about 5 to about 150, thereby effecting the conversion of 1-butylene to 2-butylene as the predominant reaction, said bauxite having first been subjected to a temperature of from about 500° C. to about 800° C. thereby rendering said bauxite active for the conversion of 1-butylene to 2-butylene in said conversion temperature range.

5. A process for the production of 2-butylene from a hydrocarbon mixture comprising 1-butylene and isobutylene, which comprises contacting said hydrocarbon mixture in a first conversion zone with a catalyst comprising bauxite at a temperature of from about 300° C. to about 375° C. and at a liquid hourly space velocity of from about 10 to about 25, thereby effecting the conversion of 1-butylene to 2-butylene as the predominant reaction, said bauxite having first been subjected to a temperature of from about 500° C. to about 800° C. thereby rendering said bauxite active for the conversion of 1-butylene to 2-butylene in said conversion temperature range, separating a fraction comprising 2-butylene and a fraction comprising isobutylene from the effluence of the first conversion zone, contacting said fraction comprising iso-

butylene in a second conversion zone with a catalyst comprising alumina at a temperature of from about 450° C. to about 550° C. and at a liquid hourly space velocity of from about 1 to about 10, thereby effecting the conversion of isobutylene to normal butylenes as the predominant reaction, separating a fraction comprising 2-butylenes and a fraction comprising 1-butylenes from the effluence of said second conversion zone, and passing said fraction comprising 1-butylenes to the first 10 conversion zone.

6. A process for the production of 2-butylene from a hydrocarbon mixture comprising 1-butylene and isobutylene, which comprises contacting said hydrocarbon mixture in a first conversion zone with a catalyst comprising bauxite at a temperature of from about 275° C. to about 400° C. and at a liquid hourly space velocity of from about 5 to about 150, thereby effecting the conversion of 1-butylene to 2-butylene as the predominant reaction, said bauxite having first been subjected to a temperature of from about 500° C. to about 800° C. thereby rendering said bauxite active for the conversion of 1-butylene to 2-butylene in said conversion temperature range, separating a fraction comprising 2-butylene and a fraction comprising isobutylene from the effluence of the first conversion zone, contacting said fraction comprising isobutylene in a second conversion zone with a catalyst comprising alumina at a temperature of from about 400° C. to about 600° C. and at a liquid hourly space velocity of from about 1 to about 15, thereby effecting the conversion of isobutylene to normal butylenes as the predominant reaction, separating a fraction comprising 2-butylene and a fraction comprising 1-butylene from the effluence of said second conversion zone, and passing said fraction comprising 1-butylene to the first conversion zone.

7. A process for the production of 2-butylene from a hydrocarbon mixture comprising 1-butylene and isobutylene, which comprises contacting said hydrocarbon mixture in a first conversion zone with a catalyst comprising bauxite at a temperature of from about 275° C. to about 400° C. and at a liquid hourly space velocity of from about 5 to about 150, thereby effecting the conversion of 1-butylene to 2-butylene as the predominant reaction, said bauxite having first been subjected to a temperature of from about 500° C. to about 800° C. thereby rendering said bauxite active for the conversion of 1-butylene to 2-butylene in said conversion temperature range, separating a fraction comprising 2-butylene and a fraction comprising isobutylene from the effluence of the first conversion zone, contacting said fraction comprising isobutylene in a second conversion zone with a catalyst comprising alumina at a temperature of from about 400° C. to about 600° C. and at a liquid hourly space velocity of from about 1 to about 10, thereby effecting the conversion of isobutylene to normal butylenes as the predominant reaction, separating a fraction comprising 2-butylene and a fraction comprising 1-butylene from the effluence of said second conversion zone, and passing said fraction comprising 1-butylene to the first conversion zone.

8. A process for the production of 2-butylene from a hydrocarbon mixture comprising 1-butylene and isobutylene, which comprises contacting said hydrocarbon mixture in a first conversion zone with a catalyst comprising bauxite at conditions effecting the conversion of 1-butylene to 2-butylene as the predominant reaction, said bauxite having first been subjected to a tempera-

ture of from about 500° C. to about 800° C. thereby rendering said bauxite active for the conversion of 1-butylene to 2-butylene in said conversion temperature range, separating a fraction comprising 2-butylene and a fraction comprising isobutylene from the effluence of the first conversion zone, contacting said fraction comprising isobutylene in a second conversion zone with a catalyst comprising alumina at conditions effecting the conversion of isobutylene to normal butylenes as the predominant reaction, separating a fraction comprising 2-butylene and a fraction comprising 1-butylene from the effluence of said second conversion zone, and passing said fraction comprising 1-butylene to the first conversion zone.

15. The process for the production of 2-butylene
from a hydrocarbon mixture comprising 1-butylene and isobutylene in admixture with 2-butylene, normal butane and isobutane, which comprises
20 separating a fraction comprising 1-butylene, isobutylene, and isobutane from said hydrocarbon mixture, contacting said fraction in a first conversion zone with a catalyst comprising bauxite at a temperature of from about 275° C. to about 400° C. and at a liquid hourly space velocity of from about 5 to about 150, thereby effecting the conversion of 1-butylene to 2-butylene as the predominant reaction, said bauxite having first been subjected to a temperature of from about 500° C. to about 800° C. thereby rendering said bauxite active for the conversion of 1-butylene to 2-butylene in said conversion temperature range, separating a fraction comprising 2-butylene, and a fraction comprising isobutane from the effluence
30 of the first conversion zone, contacting the remaining effluence of the first conversion zone comprising isobutylene in a second conversion zone with a catalyst comprising alumina at a temperature of from about 400° C. to about 600° C.
35 and at a liquid hourly space velocity of from about 1 to about 10, thereby converting isobutylene to normal butylenes as the predominant reaction, separating a fraction comprising 2-butylene and a fraction comprising 1-butylene from the effluence of the second conversion zone, and
40 passing said fraction comprising 1-butylene to the first conversion zone.

10. The process for the production of 2-butylene from a hydrocarbon mixture comprising 1-butylene and isobutylene in admixture with 2-butylene, normal butane and isobutane, which comprises separating a fraction comprising 1-butylene, isobutylene and isobutane from said hydrocarbon mixture, contacting said fraction in a first conversion zone with a catalyst comprising bauxite under conditions effecting the conversion of 1-butylene to 2-butylene as the predominant reaction, said bauxite having first been subjected to a temperature of from about 500° C. to about 800° C. thereby rendering said bauxite active for the conversion of 1-butylene to 2-butylene in said conversion temperature range, separating a fraction comprising 2-butylene and a fraction comprising isobutane from the effluence of the first conversion zone, contacting the remaining effluence of the first conversion zone comprising isobutylene in a second conversion zone with a catalyst comprising aluminum oxide under conditions effecting the conversion of isobutylene to normal butylenes as the predominant reaction, separating a fraction comprising 2-butylene and a fraction comprising 1-butylene from the effluence of the second conversion zone, and passing said fraction comprising 1-butylene to the first conversion zone.

11. The process for the production of 2-butylene from a hydrocarbon mixture comprising 1-butylene and isobutylene in admixture with isobutane, which comprises contacting said hydrocarbon mixture in a first conversion zone with a catalyst comprising bauxite under conditions effecting the conversion of 1-butylene to 2-butylene as the predominant reaction, said bauxite having first been subjected to a temperature of from about 500° C. to about 800° C. thereby rendering said bauxite active for the conversion of 1-butylene to 2-butylene in said conversion temperature range, separating a fraction comprising 2-butylene from the effluence of the first conversion zone, separating isobutane from the efflu- 15

5 ence of the first conversion zone at a rate substantially equal to that at which isobutane is introduced into the first conversion zone, contacting the remaining effluence of the first conversion zone comprising isobutylene in a second conversion zone with a catalyst comprising aluminum oxide under conditions effecting the conversion of isobutylene to normal butylenes as the predominant reaction, separating a fraction comprising 2-butylene and a fraction comprising 1-butylene from the effluence of the second conversion zone, and passing said fraction comprising 1-butylene to the first conversion zone.

HERVEY H. VOGEL
